DESIGN FOR A SHOE

Charles Morali, Forest Hill, N. Y., assignor to Delman, Inc., New York, N. Y., a corporation of New York

Application December 29, 1933. Serial No. 50,257

Term of patent 3½ years

To all whom it may concern:

Be it known that I, CHARLES MORALI, a citizen of the United States, residing in Forest Hill, Long Island, in the county of Queens and State of New York, have invented a new, original, and ornamental Design for a Shoe, of which the following is a specification, reference being had to the accompanying drawing, forming part thereof.

Fig. 1 is a perspective view showing one side of the shoe.

Fig. 2 is a perspective view showing the other side of the shoe.

I claim:

The ornamental design for a shoe, as shown.

CHARLES MORALI.
